UNITED STATES PATENT OFFICE

2,614,372

VALVE GRINDER

Louis W. Kelly, Alhambra, Calif.

Application October 2, 1948, Serial No. 52,441

13 Claims. (Cl. 51—241)

1

The present invention relates to valve grinders in particular and especially to a power-driven grinder for large poppet valve engines. More particularly the invention comprises a grinder in which the abrasive grinding wheel is driven by means of an air motor which also provides power to turn the grinder head to bring the wheel into contact with the entire circumference of the valve seat, air under pressure being fed to the motor through a supporting base unit mounted within the stem guide of the valve seat being ground.

It is a characteristic of poppet valve combustion engines that their valve seats require refinishing from time to time to remove carbon and also to eliminate the effects of wear produced by the repeated seating of the valve and by the passage of gases. In small engines the grinder may be a hand or power-driven wheel the diameter of which corresponds to the diameter of the valve seat to be refinished. In larger motors, however, the valve seat refinishing is more successfully performed by a smaller diameter grinding wheel rotating at high speed and traveling around the seat to contact the entire circumference thereof. It is to valve grinders of this last type that the present invention relates.

A preferred method of actuating the grinding wheel is by means of a directly connected air motor movable with the grinder head as it revolves to bring the wheel into contact with the circumference of the valve seat.

It is an object of the invention to eliminate the twisting of an air-conducting conduit which would result were it connected from a stationary source directly to the revolute air motor. According to the present invention the source of air power connects to the stationary part of the supporting base unit and air is conducted upwardly therethrough to the rotary head.

It is another object of the invention to make possible the use of a grinding wheel of increased diameter and so the supporting base, which includes a stationary pilot seated within the valve stem guide, is provided with an offset island to support the revolute grinder head at one side of the valve center line. The increased diameter of the grinding wheel permits of longer use without dressing and of greater accuracy.

A further object of the invention is to provide an improved grinder feed in which the grinding wheel and its actuating means are pivotally supported for radial adjustment with respect to the center of the valve seat being ground.

2

A still further object of the invention is to provide a valve grinding unit in which the grinding wheel is directly connected to the actuating motor which also functions through means including a clutch to effect the revolution of the grinding head around the valve seat, the presence of the clutch facilitating the dressing of the grinding wheel when necessary.

Still another object of the invention is to provide a valve grinding unit in which the revolute grinding head is pivotally supported upon a base and is angularly adjustable thereon to vary the effective radius of the grinding wheel under the control of a manually operable micro adjustment.

A still further object of the invention is the provision of a valve grinder in which the grinder head mounted for revolution relative to the valve seat can be given a quick rough adjustment followed by an accurate micro adjustment.

These and other more specific objects will appear upon reading the following specification and claims and upon considering the connection therewith the attached drawings to which they relate.

Referring now to the drawings in which a preferred embodiment of the invention is illustrated:

Figure 1 illustrates a valve grinder constructed in accordance with the present invention seated in operative relationship to the valve seat of an engine which is partially shown in section;

Figure 2 is a top plan view of the construction shown in Figure 1;

Figure 3 is a partial longitudinal section through the construction of Figure 1, being taken upon the line 3—3 of that figure;

Figure 4 is a section through the gear box or power take off unit upon the line 4—4 of Figure 2 and shows the power transmitting means between the motor-driven shaft of the grinding wheel and the clutch-controlled shaft which effects the revolution of the grinding head;

Figure 5 is a vertical section through the gear box unit upon the line 5—5 of Figure 4 and shows the mounting of the grinding wheel shaft;

Figure 6 is a vertical section through the gear box unit upon the line 6—6 of Figure 4 and shows the mounting of the driven shaft which effects the revolution of the grinding head;

Figure 7 is a horizontal section upon the line 7—7 of Figure 6 and shows the gear box locking bolt by which rough vertical and angular adjustment of the grinding wheel is obtained;

Figure 8 is a vertical section through the supporting base unit upon the line 8—8 of Figure 3;

Figure 9 is a vertical section through the manually adjustable cone cam by which the micro adjustment of the grinding head is obtained, the cone being shown in an initial position;

Figure 10 is a view similar to Figure 9 showing the cone in a lowered finally adjusted position; and

Figure 11 is a view in perspective of the gear box bolt per se.

In the drawings a preferred form of the present invention is illustrated and may be divided into three major parts identifiable as the grinding head unit, generally indicated by the reference character 20 and including a grinding wheel proper 21; a power take off or gear box unit 22, and a driving motor 23; a supporting base unit generally indicated by the reference character 25 including a base 26 revolvable with the head 20 and a stationary pilot 27; and a micro adjustment indicated generally by the reference character 38 by which the grinding wheel 21 is radially adjusted for use on different size valve seats and which includes among other parts to be described a frustoconical cam 31 carried by a vertical shaft 32 at the upper end of which is a manually rotatable knob 33.

In Figure 1 of the drawings the grinding head unit 20 is shown positioned operatively with respect to the valve seat of a poppet-type motor in which the block is indicated by the reference character 35, the valve chamber by the character 36, the stem guide for the unshown valve by the reference character 37, and the valve seat which is to be ground by the reference character 38, its internally threaded retaining ring bearing the reference character 39.

Directing our attention first to the grinding head unit 20, it is seen that the grinding wheel 21, which may be frustoconical and formed of a suitable abrasive, is secured at the lower end of a rotatable shaft 41 which extends vertically downwardly through a passage 42 in the gear box 22, being supported by ball bearings 43 and 44, respectively. A packing gland 46 is positioned below the lower bearing 44 and a worm gear 47 is fixed to the shaft between the bearings for a purpose to be related. The upper end of shaft 41 carries a slotted head 48 seating the rectangularly sectioned lower end of the shaft 49 of air motor 23. The lower portion of the motor casing seats in threaded relationship at 51 in a supporting sleeve mounting 52 itself threaded at 54 in the casing of gear box unit 22 immediately above the bearing 43. The air motor 23 may be of any conventional type adapted to be actuated by air under pressure and is supplied through a flexible conduit 56 to which it is connected by a connector 57. The opposite end of hose 56 extends to a suitable connector 58 opening into the base 26 of the supporting base unit 25. When the motor is supplied with air under pressure the rotation of its shaft 49 effects the rotation of the directly connected shaft 41 and of the grinding wheel 21 carried at the lower end thereof.

Grinding wheel 21 and its actuating motor 23 are supported by the gear box unit 22, also referred to as the power take-off unit, which is itself mounted for angular adjustment about a vertical axis above a horizontal platform 61 forming a part of the base 26 and carried above the major part thereof by an integral vertically extending off-center island 62. With the stationary pilot 27 of base unit 25 non-rotatably positioned within the valve stem guide 37 the base

26, also a part of the base unit 25, extends into valve seat 38, the offset island 62 being displaced at one side of the longitudinal axis of the valve seat to permit of the use of a grinding wheel 21 of larger diameter than would otherwise be possible. Gear box unit 22 is angularly adjustable upon the base 26 and its platform 61 by means which will subsequently be described. Attention is here directed, however, to the supporting base unit 25 by which the grinding head unit 20 is rotatably supported.

As stated, supporting base unit 25 includes the rotatable base 26 and a stationary pilot 27. The latter extends through the valve stem guide 37 in which the engine valve reciprocates vertically in the normal operation of the engine. The upper end of the pilot is expanded conically at 67 so that it will center itself and seat within stem guides of varying internal diameters. Its lower end is threaded at 68 to seat a pilot nut 69 formed with a knurled enlargement at 71 for ease in manual rotation and with a tapered upper end at 72. The latter functions in the manner of surface 67 and enables it to seat and to center itself within stem guides of various internal diameters. The tightening of the nut 69 draws the pilot 27 downwardly and positions it fixedly and non-rotatably with respect to the stem guide 37 so that its upper end provides a fixed support for the base 26. The latter is rotatably supported upon the pilot 27 by means of upper and lower ball bearings 73 and 74, respectively.

Incoming air to the driving motor 23 is fed upwardly through the supporting base unit 25 entering the pilot nut 69 at a rotatable connector 76 connected at its outer end by an L connector 77 to an incoming air conduit 78. Pilot 27 is itself provided with a central bore 79 functioning as an air conduit into the upper end of which a nozzle 81 extends downwardly from the rotatable base 26, being seated with respect thereto by a sealing gland 82. At its upper end nozzle 81 connects through a transverse passage 84 in base 26 to the threaded connector 58. As previously described, connector 58 is itself connected to the flexible conduit 56 leading to the air motor 23. It is seen, then, that the motor actuating air enters the lower end of the pilot 27 to be conducted upwardly therethrough to the rotatable base 26, thence through the nozzle 81 to conduit 56, and so to the motor 23.

The construction described mounts the grinding wheel 21 with respect to the valve seat 38 and provides for its rotation about its own axis. It is additionally necessary to provide for the travel of the wheel around the circumference of the valve seat. This is accomplished by effecting the rotation of the base 26 of the supporting base unit 25 upon its supporting pilot 27 by means which will now be described.

Within the gear box unit 22 a transverse passage 91 is provided in which extends a shaft 92 rotatably supported in bearings 93 and 94 retained against longitudinal displacement by threaded positioning spacers 96 and 97, respectively. Adjacent the worm 47 carried by grinding wheel shaft 41 transverse shaft 92 carries a pinion 98 so that upon the operation of the air motor shaft 92 is rotated. Adjacent its opposite end shaft 92 carries a worm 99 engaging a pinion 101 positioned in a second vertical passage 102 similar and parallel to passage 42. Pinion 101 is fixed on the lower end of a hollow sleeve 103 rotatable in a bushing 104 threaded into the end 75 of passage 102 and carries at its own upper end

a transversely slotted female clutch member 106. A vertical shaft 107 extends through the sleeve 103, its upper end being irregular in section, as for example square, and slidably seats a male clutch element 108 adapted to engage the first-mentioned clutch element 106 to clutch the shaft to the sleeve 103. As is shown most clearly in Figure 8 the lower end of shaft 107 carries a pinion 111 within the base 26 of supporting base unit 25 in mesh with a center gear 112 fixed to the upper end of non-rotatable pilot shaft 27. The rotation of shaft 107 causes the pinion 111 to travel as a planet gear about the center gear 112 as a sun gear to effect the rotation of base 26 and with it the grinding head unit 20 carried thereby.

In addition to the rotation of grinding wheel 21 and its revolution about the longitudinal axis of the valve seat mechanism it is also necessary to provide for the vertical and radial adjustment of the wheel to enable it to function in different valve seats. According to the present invention this adjustment means comprises an initial rough adjustment and a final micro adjustment. The lower end of shaft 107 extends through an elongated vertically extending bored post 116 seated threaded in the island 62 of base 26. The platform 61, previously referred to, is clamped between a shoulder 117 on the post and the island. A concentric sleeve 118 encloses post 116 within the vertical passage 102 of unit 20 and is rotatable relative thereto being secured against longitudinal displacement relative to the post by a nut 119 threaded on the upper end of the post. From the lower end of sleeve 118 a lever 121 extends parallel to and above platform 61 which is fixed to and forms a part of base 26. Vertical passage 102 in gear box unit is intersected by a horizontally extending bore 121 in which is positioned a locking bolt 122 formed with a cut-out sector 123 shaped to conform to the curvature of sleeve 118. The threaded outer end of bolt 122 carries a nut 124 which, when tightened, draws the bolt 122 outwardly as to lock the sleeve 118 and the gear box 22 against relative longitudinal or arcuate displacement. With nut 124 loosened gear box unit 22 may be adjusted angularly with respect to the sleeve 118 to vary the radial extension of wheel 21. It may also be adjusted vertically to vary the vertical position of the wheel.

The micro adjustment of the grinding wheel 21 is accomplished by the manual adjustment of the frustoconical cam 31, the supporting shaft 32 of which seats threaded for vertical adjustment upon a fixed threaded post 126 clamped by a nut 127 in its threaded relationship to the base platform 61.

As is clearly illustrated in Figures 9 and 10, platform 61 carries a retaining seat 131 upon its upper surface for a coil spring 132 the opposite end of which extends into a similar seat 133 formed at the outer end of lever 121 fixed to sleeve 118. Coil spring 132 tends at all times to force the end of lever 121 against the surface of cam 31 and the angular position of the lever is determined by the vertical adjustment of the cam which is manually positionable by the rotation of shaft 32 under a torque exerted at its knurled upper end 33. With the nut 124 tightened upon the locking bolt 122 gear box unit 22 is fixed with respect to sleeve 118 and any further angular adjustment thereof, and so of the grinding wheel 21 carried thereby, is accomplished by the rotation of the sleeve 118 relative to the post 116 under the actuation of the cam 31.

In the operation of the grinding unit constructed in accordance with the present invention the unit would be positioned relative to the block of the motor as illustrated in Figure 1, the pilot 27 being extended downwardly through the valve guide stem 31. Pilot nut 69 would then be threaded upon the lower end of the pilot to draw the conical upper end 67 thereof downwardly into seating relationship with the upper end of the guide 37. The air conduit 78 at the lower end of the pilot could then be connected to a source of air under pressure. It is assumed that the grinding wheel 21 has been suitably dressed as by contact with a diamond stone. The operator then rotates the cone shaft 32 by turning its knurled top 33 until the small end of the cone just engages the top of the lever 121, as illustrated in Figure 9. He then loosens the gear box locking bolt 122 by unscrewing its nut 124 and angularly adjusts as well as raises or lowers the box with respect to the sleeve 118 and the supporting post 116 which it surrounds. The gear box unit 22 is lowered until the grinding wheel 21 almost touches the valve seat face in the relationship illustrated in Figure 1. Gear box locking bolt 122 is then tightened by its nut 124 and the box unit is fixed with respect to the sleeve 118 and its attached lever 121. The fine micro adjustment is then accomplished by the manual rotation of the cone shaft 32, the air to the actuating motor 23 first being turned on. Cam 31 is lowered on its supporting stud 126 by the rotation of shaft 32 effecting the pivotal movement of the gear box unit about the supporting stud 116 until the grinding wheel 21 makes satisfactory contact with the valve seat.

The rotation of the wheel 21 under power supplied by motor 23 is accompanied by the simultaneous revolution of the grinding head unit 20, the rotation of the wheel-connected shaft 41 being transmitted through the gears 47, 98 to the transverse shaft 92, driving the vertical shaft 107 through gears 99 and 101, sleeve 103 and the clutch 106, 108. The grinding head unit revolves at a speed much less than that of wheel 21, the speeds being in the ratio of 1000 or 1500 to 1. If it is desired to discontinue the revolution of the grinding head unit it is only necessary to lift the clutch element 108 upon shaft 107 as to disengage it from the continuously rotating clutch element 106. Thereupon the grinding wheel rotates while the grinding head does not revolve. This relationship is frequently desirable as in truing up the face of the wheel or in giving it the proper angle for grinding a narrow seat.

While the particular apparatus herein shown and described in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

I claim:

1. A valve grinder comprising a revoluble grinding head unit including a rotary grinding wheel and an air motor connected thereto, a supporting base unit including a base supporting said head unit and itself revolvably mounted upon a stationary pilot adapted to extend into the stem guide of the valve the seat of which is being ground, and an air conduit system to supply actuating air to said air motor including

an air passage in said base and a connected passage extended through said pilot including the portion thereof adapted to extend through said stem guide.

2. A valve grinder comprising a revoluble grinding head unit including a rotary grinding wheel and an air motor connected thereto, a supporting base unit including a base supporting said head unit and itself revolubly mounted upon a stationary pilot adapted to extend into the stem guide of the valve the seat of which is being ground, said base and said pilot below said base and through said stem guide being provided interiorly with air-conducting passages including a joint having relatively rotatable parts, and an air conduit connected to said base to conduct air therefrom to said air motor.

3. A valve grinder comprising a grinding head unit including a rotary grinding wheel, a driving motor direct connected thereto, and a power take off unit, a rotatable supporting base unit including a base supporting said head unit for pivotal movement about a pivotal axis parallel to and displaced from a central axis to vary the radial distance of said wheel from said central axis, and a stationary pilot in said central axis rotatably supporting said base adapted to seat in the stem guide of the valve the seat of which is to be ground, a rotary shaft extended between said power take off unit and said base and connected to said power take off unit through means including a clutch, and means to effect the rotation of said base about said pilot upon the rotation of said shaft.

4. A valve grinder comprising a grinding head unit including a rotary grinding wheel, a driving motor direct connected thereto, and a power take off unit, a supporting base unit including a base supporting said head unit for pivotal movement about a pivotal axis parallel to and displaced from a central axis and a stationary pilot in said central axis rotatably supporting said base and adapted to seat in the stem guide of the valve the seat of which is to be ground, a rotary shaft extended between said power take off unit and said base connected to said power take off unit through means including a clutch, and means to effect the rotation of said base comprising a planet gear on said shaft and a sun gear fixed to said pilot.

5. A valve grinder comprising a grinding head unit including a rotary grinding wheel, a driving motor direct connected thereto, and a power take off unit, a supporting base unit including a base supporting said head unit for pivotal movement about a pivotal axis parallel to and displaced from a central axis and a stationary pilot in said central axis rotatably supporting said base and adapted to seat in the stem guide of the valve the seat of which is to be ground, a rotary shaft extended between said power take off unit and said base in said displaced axis, means to effect the rotation of said base upon the rotation of said shaft, and cooperative means upon said base and said head unit to adjust said head unit angularly about said displaced axis to vary the radial extension of said grinding wheel from said central axis.

6. A valve grinder comprising a grinding head unit including a rotary grinding wheel, a driving motor connected thereto, and a power take off unit, a supporting base unit including a base supporting said head unit for pivotal movement about a pivotal axis displaced from a central

5 axis and a stationary pilot in said central axis rotatably supporting said base adapted to seat in the stem guide of the valve the seat of which is to be ground, a rotary shaft extended between said power take off unit and said base, a planet gear fixed to the lower end of said shaft in said base, a sun ring gear fixed to the upper end of said pilot in said base, the rotation of said planet gear with said shaft causing said base and head unit to revolve around said central axis, a lever forming a part of said head unit extended laterally adjacent a platform rigid with said base, spring means urging said lever and head unit in one direction about said pivotal axis, and manually adjustable means to move said lever and said head unit in the opposite direction about said pivotal axis to vary the radial extension of said grinding wheel from said central axis.

7. The construction recited in claim 6 characterized in that said pilot and base form a part of the air conduit system to convey air to actuate said driving motor and in that a nut threadedly seated on the lower end of said pilot draws the upper end thereof downwardly against the upper end of said valve stem guide through which it extends.

8. A valve grinder comprising a grinding head unit including a rotary grinding wheel, an air motor direct connected thereto, and a power take off unit, a supporting base unit including a base supporting said head unit for pivotal movement about a pivotal axis displaced from a central axis and a stationary pilot supporting said base for rotation about said central axis and adapted to seat in the stem guide of the valve the seat of which is to be ground, a rotary shaft extended between said power take off unit and said base, said power take off unit including speed reducing means connecting said shaft to said driving motor to effect the rotation thereof at reduced speed, means to effect the rotation of said base upon the rotation of said shaft, and an air conduit system to feed actuating air to said air motor including an air passage in said base and an air passage extended interiorly through the portion of said pilot adapted to seat in said stem guide, said pilot being adapted to connect to a source of air under pressure below said guide.

9. A valve grinder comprising a grinding head unit including a rotary grinding wheel and a driving air motor therefor, a source of actuating air for said motor including a rigid air conduit adapted to seat non-rotatably in the stem guide of a valve the seat of which is to be ground, means mounting said head unit for rotation about said rigid conduit as an axis, and air-conducting means to conduct air from said rigid air conduit to said air motor in all rotational positions of said motor around said rigid conduit.

10. A valve grinder comprising a grinding head unit including a rotary grinding wheel and a driving air motor therefor, a source of actuating air for said motor including a rigid air conduit adapted to seat non-rotatably in the stem guide of a valve the seat of which is to be ground, means mounting said head unit for rotation about said rigid conduit as an axis, means to revolve said head unit around the axis of said rigid air conduit upon the actuation of said motor, and air-conducting means to conduct air from said rigid air conduit to said air motor in all rotational positions of said motor around said rigid conduit.

11. A valve grinder comprising a grinding head unit including a rotary grinding wheel and a driv-

ing motor therefor, a supporting base unit including a base revolvably supporting said head unit and a non-rotatable pilot adapted to seat in a valve stem guide rotatably to support said base, means supporting said grinding head unit for selective angular adjustment on said base to vary the radial extension of said wheel relative to the axis of a valve seat including means supporting said head unit on said base for relative rotation about a parallel axis spaced from the axis of said pilot, and manually operable micro adjusting means to pivot said head unit about said parallel axis, characterized in that said micro adjusting means includes a lever arm movable with said head unit and a manually rotatable cam to pivot 15 said lever arm.

12. A valve grinder comprising a grinding head unit including a rotary grinding wheel and a driving motor therefor, a supporting base unit including a base revolvably supporting said head unit and a non-rotatable pilot adapted to seat in a valve stem guide rotatably to support said base, means supporting said grinding head unit for selective angular adjustment on said base to vary the radial extension of said wheel relative to the axis of a valve seat including means supporting said head unit on said base for relative rotation about a parallel axis spaced from the axis of said pilot, and manually operable micro adjusting means to pivot said head unit about said parallel axis, characterized in that said micro adjusting means includes a lever movable with said head unit urged in one direction by a spring abutting said base and in contact with a manually adjustable cam carried by said base and adapted to be 35 moved thereby in the opposite direction.

13. A valve grinder comprising a grinding head unit including a rotary grinding wheel and a driving motor therefor, a supporting base unit including a base revolvably supporting said head unit and a non-rotatable pilot adapted to seat in a valve stem guide rotatably to support said base, means supporting said grinding head unit for selective angular adjustment on said base to vary the radial extension of said wheel relative to the axis of a valve seat including means supporting said head unit on said base for relative rotation about a parallel axis spaced from the axis of said pilot, and manually operable micro adjusting means to pivot said head unit about said parallel axis, characterized in that said micro adjusting means includes a lever movable with said head unit spring-urged in one direction into contact with a cone cam carried by a manually rotatable shaft mounted for rotation on and for movement toward and from said base.
